UNITED STATES PATENT OFFICE

FREDERICK G. MALONEY, HENRY R. VOGEL, AND HERBERT B. WHEELER, OF WINONA,
MINNESOTA

SIGN-OPERATING DEVICE

Application filed October 2, 1926. Serial No. 139,077.

This invention relates to a sign or signal device, and while the invention is capable of many applications, it particularly is designed for use in street cars or similar conveyances traversing fixed routes and having designated stops. Modern street cars and similar conveyances make stops at certain streets or other designated places and the conductor usually calls the street or stop. It is often difficult for the passengers to hear what the next stop is to be and confusion and difficulty are experienced by passengers especially those who are unfamiliar with the route.

15 It is an object of this invention to provide a simple and efficient device which will indicate the next stop to be made by the car or other vehicle and which may be easily operated by the conductors so that it will be
20 unnecessary to call the street or stop.

It is a further object of the invention to provide such a device comprising a movable member having inscribed thereon the designations of the stops and which is intermittently movable by the conductor or operator to successively display the said designations.

It is another object of the invention to provide such a device comprising an endless member having the designations of the stops thereon, together with means for displaying one of said designations, which member has means actuated by the operator for moving the same to display different designations, the device having automatic means for stopping said movable member with one of the designations displayed.

It is still another object of the invention to provide such a device as set forth in the preceding paragraph in which the endless 40 movable member may be reversed and thus intermittently moved in either direction.

These and other objects and advantages of the invention will be fully set forth in the following description made in connection with the accompanying drawings, in which like reference characters refer to similar parts throughout the several views and in which:—

Fig. 1 is a view partly in plan and partly in horizontal section of the device;

Fig. 2 is a view partly in front elevation and partly in vertical section of the device, certain parts being broken away;

Fig. 3 is a vertical section taken on line 3-3 of Fig. 2, as indicated by the arrows; and

Fig. 4 is a horizontal section taken on line 4-4 of Fig. 3, as indicated by the arrows.

Referring to the drawings, a device is shown comprising a base member 6 illustrated as of platelike form and rectangular in shape.

as of platelike form and rectangular in shape. The base member 6 carries a casing 7 also illustrated as of rectangular form, which casing has bearings at opposite sides thereof for a plurality of shafts 8, 9, 10 and 11 respective-

ly, which extend from side to side thereof. The casing 7 also has a rectangular opening

7^a surrounded by a flange 7^b. While this opening may be disposed in various parts of the casing, in the embodiment of the invention illustrated it is shown as at the front

thereof. The casing 7 also has the inscription "Next. Stop" thereon below the opening 7a. The shafts 8, 9, 10 and 11 respectively

ly have secured thereto rolls 12, 13, 14 and 15. A member of paper or flexible sheet material 16 has its ends secured respectively to

the rolls 14 and 15 and extends over the top of the rolls 12 and 13 and is guided parallel to the front of casing 7 and in front of the

opening 7^a, said member running over small guide rollers 17 disposed adjacent the top and bottom of said opening and carried on shafts

also journaled in the sides of the casing 7. The member 16 has secured thereto at one side a plurality of spaced members 18 which

project some distance above the surface of said member. The member 16 also has inscribed thereon designations of the stops to

be made by the vehicle, one of said designations, "Main Street", being shown in alignment with opening 7^a. Tension members com-

prising spring arms 16^a secured to and up-
standing from casing 7 engage member 16
on rolls 14 and 15 and prevent too rapid un-

circles 14 and 15 and prevent too rapid air-rolling thereof. The shafts 10 and 11 project at one side of the casing 7 and have secured thereto, respectively, gears 19 and 20.

cared thereto respectively gears 19 and 20. The gear 19 meshes with an idler gear 21 journaled on a stub shaft 22 which is secured in the side of casing 7. The gears 20 and 21

are adapted to mesh with a driving gear 23 carried on a shaft 24 which is journaled in a movable bearing 25 secured to the base member 6 by bolts or screws 26 projecting through parallel slots 25^a in the base thereof, whereby the bearing 25 will be guided rectilinearly by said slots and bolts. The bearing 25 is adapted to be moved by a hand lever 27 having a slot 27^a at one end through which extends a screw 28 secured in a projection extending from the base of the bracket 25. The lever 27 is intermediately pivoted to the base 6 and has a pin 27^b secured therein adapted to be engaged in either one of a pair of holes 29^a formed in a segmental plate 29 also secured to base 6. When pin 27^b is in one of said holes 29^a, the gear 23 meshes with gear 19 and when said pin is in the other of said holes, the gear 23 is in mesh with gear 21. The shaft 24 has a worm wheel gear 30 secured thereto at one side of the bracket 25 meshing with a worm gear 31 which is carried on the armature shaft 32 of an electrical motor 33 mounted on a base 34 which is in turn secured to the base 6. The circuit for motor 33 is diagrammatically indicated in Fig. 3 and will be supplied with current in the usual manner from line conductors 35 by a switch 36 which may be of any usual and suitable construction. The circuit for the motor includes the conductors 37 and said circuit may be closed by a switch 38 which preferably will be in the form of a push button switch and will be disposed in a convenient position for manipulation by the conductor or operator. A pair of conductors 39 also extend in parallel with conductors 37 and the conductors 39 are secured respectively to binding posts or screws 40 and 41 secured in the casing 7. A switch lever 42 is intermediately pivoted on the screw 40 and is acted upon by coil spring 43 disposed about screw 40 to keep one end thereof in contact with the screw 41 so that conductors 39 normally are connected by the switch 42. The switch or lever 42 is bifurcated at one end and has journaled therein a roller 44 which preferably will be made of insulating material. The roller 44 is positioned so that it is held against and rolls in contact with the upper surface of the member 16 substantially above the roll 13 and said roller is alined with the members 18 which pass beneath the same.

In operation the device will be carried or disposed at some point in the street car or other vehicle where the passengers may readily view the designations displayed through the opening 7^a in casing 7. When the vehicle starts at one end of its route, the member 16 will be largely wound on one of the rollers 14 or 15 and at this time the first stop will be displayed through the opening 7^a. At this time also, one of the projections 18 will be under the roller 44 and switch lever 42 will be out of contact with screw 41 and the

switch will thus be opened. If the stop displayed has been passed, the conductor will operate the switch 38 which, as stated, will be in the form of a push button or some easily operated switch and thus will close the circuit of the motor 33. When switch 38 is momentarily closed, the motor will start and as shown in Fig. 1, will drive roller 14 through gears 31, 23 and 19. As soon as the member 16 is moved, the member 18 will move from beneath roller 44 and the motor circuit will then also be closed through the conductors 37 and 39. The switch 38 need thus only be momentarily closed. The motor will now continue to run and the member 16 be moved until the next projection 18 passes under the roller 44. This will raise one end of roller 44 and move its other end out of contact with screw 41, thus opening the motor circuit at this point. The motor will now be stopped and the next designation on member 16 will be brought into alinement with opening 7^a and displayed therethrough. The conductor or operator, therefore, need only operate the switch 38 as the successive stops are passed, and the next stop will then be displayed. The passengers can thus readily see what the next stop is and will have no difficulty in locating their desired stop. When the vehicle has reached the end of its route and is to return, the conductor or operator will move the lever 27, placing the pin 27^b in the other hole 29^a. This will shift bracket 25 and gear 23 so that the latter moves out of mesh with gear 19 and moves into mesh with gear 21. With this arrangement of gearing the direction of movement of member 16 will be reversed and the member 16 will be driven by the roll 15 instead of the roll 14 and will be wound up on the roll 15 and unwound from the roll 14. The designations of the stops will thus be displayed in reverse order as the vehicle returns over the route it has just traversed.

From the above description it is seen that the applicant has provided a very simple and efficient display device for successively displaying the designations of the stops as the car or vehicle moves over its route. It is thus unnecessary for the conductor to call the stops and he need merely press a button and the stops are displayed. The device is very simple and easily operated. The same has been amply demonstrated in actual practice and found to be very successful and efficient.

It will, of course, be understood that various changes may be made in the form, details, arrangement and proportions of the parts, without departing from the scope of applicants' invention, which, generally stated, consists in a device capable of carrying out the objects above set forth, in the novel parts and combinations of parts disclosed and defined in the appended claim.

What is claimed is:—

A sign display device having in combination, a movably mounted flexible sheet having a plurality of stop designations thereon, a casing having an opening past which said sheet moves, said opening being of a size that one designation may be observed therethrough when properly aligned therewith, an electric motor, means for moving said sheet 5 in either direction driven by said motor, said sheet having a plurality of spaced projections thereon, a contact member constituting a stop disposed adjacent said sheet, a pivoted arm having one end disposed over said sheet so 10 as to be engaged by said projections and movable toward said sheet by gravity, the other end of said arm being adapted to engage said contact member, said latter end being moved out of engagement with said contact 15 member when said first mentioned arm is engaged by one of said projections, a circuit for said electric motor adapted to be closed by contact between said contact member and the last mentioned end of said arm and a 20 manually operable switch for closing said circuit independently of said arm and contact member whereby said motor circuit may be momentarily closed by said switch and said sheet will be driven by said motor until one 25 of said projections engages said arm, when said circuit will be opened and movement of said sheet is stopped.

In testimony whereof we affix our signatures.
